UNITED STATES PATENT OFFICE.

MILLARD J. ROBERTS, OF BUFFALO, NEW YORK, ASSIGNOR TO ROBERTS-GORDON APPLIANCE CORPORATION, OF BUFFALO, NEW YORK, A CORPORATION OF NEW YORK.

GAS BURNER AND THE LIKE.

Application filed January 6, 1928. Serial No. 244,884.

This invention relates to heating devices, and particularly to the use of gas or fluid fuel burners in heaters of the solid fuel burning type.

5 An object of this invention is to improve heaters operated by fluid fuels, and increase their efficiency.

Another object of the invention is to provide an improved fluid fuel burner for use 10 in existing types of heaters originally designed for the use of solid fuel; with which such heaters may be operated with gas or other fluid fuel in an efficient and economical manner; with which a maximum possible 15 heat transfer from the burning fuel to the heating device may be obtained; which may be applied to heaters having fire pots of different sizes; with which the hot gases of combustion may be effectively confined in 20 proximity to the fire pot walls; and which will be relatively simple, efficient and inexpensive.

A further object of the invention is to provide an improved radiant element which may 25 be used with heaters which have been arranged for the use of fluid or gaseous fuel.

Various other objects and advantages will 30 be apparent from the following description of an embodiment of the invention, and the novel features will be particularly pointed 35 out hereinafter in connection with the appended claims.

In the accompanying drawing:—

Fig. 1 is a face elevation of a radiant element constructed in accordance with this 35 invention;

Fig. 2 is one side elevation of the same;

Fig. 3 is another side elevation of the same;

40 Fig. 4 is one end elevation of the same;

Fig. 5 is the opposite end elevation of the same;

Fig. 6 is a sectional elevation of the same, with the section taken approximately along 45 the line 6—6 of Fig. 1;

Fig. 7 is a sectional elevation of a portion of a fire pot and burner, with one of the improved radiant elements in operative position;

50 Fig. 8 is a perspective illustrating the application of the invention to a coal burning boiler of the household heating type, which has been arranged for the use of gaseous fuel in accordance with this invention;

55 Fig. 9 is a sectional plan of a portion of

the same on a larger scale, the section being taken through the fire pot just above the radiant elements; and

Fig. 10 is a perspective of one of the radiant elements.

In the illustrated embodiment of the invention, the invention is incorporated in a boiler 1 (Fig. 8) of the type commonly utilized for heating residences or small buildings. A gas burner 2 is mounted within the fire pot 3 of this boiler 1 at the bottom of the fire pot, the burner being of arcuate or circular ring type which extends adjacent and along the lateral or side wall of the fire pot. Such a burner may have openings 4 through which the gas mixture to be burned emerges. One chamber 2^a (Fig. 7) of the burner ring may be supplied with gas and air by suitable pipes 5, each extending outwardly through the ashpit door 6 and terminating in an adjustable air and gas mixing valve 7 of suitable construction. Additional and auxiliary air may be admitted to the other chamber 2^b of the burner ring through a duct 8 which is connected to the ring and opens into a chamber 2^b, the duct 8 extending through the ash pit door. The outer end of the duct 8 is controlled by a suitable damper or door 9. The door 9 is operated by cable 10 from a thermostatically controlled motor or device 11, and the cable 10 is connected to and also operates a valve 12 provided in the gas supply pipe 13 leading to the mixing devices 7. Hence, when the valve 12 is operated to cut off the supply of fuel, the door 9 will be closed to prevent the entrance of air into the fire pot.

The upper face of burner ring 2 may be provided with annular ribs 14 concentric with one another. A plurality of radiant elements 15 in the form of plate-like strips are supported endwise upon the upper face of the burner ring, inside of the row of burner openings 4, and allowed to lean against the firepot wall. The radiant elements will thus be supported in inclined or oblique positions above the burner openings 4, so as to be in the path of the flames from such openings, and the lower ends will be held against sliding by the ribs 14. The radiant elements 105 may be made of any suitable material which is fire resistant and capable of absorbing and radiating heat, such materials being well known in the art.

The radiant elements may have the form 110

of plate-like strips tapering in width from end to end, and the under faces adjacent their upper and wider ends have a somewhat concave surface 16, so that when the 5 upper and wider end of each element leans against the firepot wall, the concave surface 16 will provide a shallow channel between the strip and the fire pot wall through which the gases of combustion from the burner 10 may pass in reaching the upper part of the combustion chamber and then the chimney or discharge flue. The under face of each of these elements may also be provided with a plurality of relatively small pronounced 15 projections or protuberances 17 which may be engaged directly by the flames leaving the burner openings 4, and it has been found that by the use of such projections, the radiating elements will take up by conduction 20 a considerable quantity of heat from the flames and gases of combustion, and will radiate this absorbed heat directly towards the fire pot wall.

The tapered radiant elements are arranged 25 side by side and progressively overlapped in a shingle-like manner. Diagonally opposite side edges of each strip are bevelled to provide contact faces 18 and 19. These bevelled or oblique faces permit of various degrees 30 of overlap of the radiant elements, and have surfaces which are of the type geometrically known as warped surfaces. The warping occurs progressively from end to end of each element, and by reason of these warped surfaces 35 which overlap one another, the elements may be overlapped to different extents, or spread out to various extents in a fan-like manner, and still have a continuous contact with one another along the entire 40 lengths of the overlapping faces. The firepots of different heating plants vary considerably in size, and hence the inclination of the radiant elements will vary considerably when installed in different fire pots. The 45 same size radiant elements may be used for all of the usual heaters, even when of different sizes, the warped surfaces 18 and 19 permitting the fan-like spreading of the upper ends as they fit the firepots of different sizes. 50 By having contact continuous along the overlapped faces, the gases of combustion from the burner ring will be more effectively confined to the chamber between the radiant elements and the fire pot and compelled to 55 pass upwardly along the radiant elements and through the channels formed by the concave surfaces 16.

By the use of radiant elements in the manner hereinbefore described and illustrated, 60 effective use is made of radiant heat which is the most effective of the three different forms of heat, to wit, conducted, convected and radiant heat. These radiant elements cause friction of the flames against the furnace walls, and by confining the flames in prox-

imity to the fire pot wall, they largely prevent undesired dissipation of the intense heat of the flames to the interior of the fire pot or heating chamber, where a heat transfer to the fire pot walls is impossible or less 70 efficient and by taking up conducted heat from the flame and radiating it as radiant heat towards the fire pot walls, a more effective heat transfer to the firepot walls is obtained. The radiant elements become very 75 hot and superheat the gases coming from the burner, and thus insure a complete combustion of the fuel. When the burners are shut off by the thermostatically controlled motor or device 11, the door 9 will be closed, and thus no further air can enter the duct leading to the air chamber 2^b of the burner ring or enter the fire pot, and thus cool the radiant elements. These radiant elements which have previously been heated to a high temperature will slowly radiate the absorbed 80 heat to the fire pot walls and insure a continuance of heat transfer to the fire pot walls long after the burners have been shut down.

It will be obvious that various changes in 85 the details, which have been herein described and illustrated, in order to explain the nature of the invention, may be made by those skilled in the art within the principle and scope of the invention as expressed in the appended claims.

I claim as my invention:—

1. A gas burner for use in heating devices having a fire box, comprising a burner disposed in said fire box and extending along and adjacent the wall thereof, radiant wall elements disposed obliquely across the flame from said burner and towards said wall, for radiating towards said wall heat which it absorbs from said flame, said elements being progressively overlapped side by side in a shingle-like manner.

2. A gas burner for use in heating devices having a fire box, comprising a burner disposed in said fire box and extending along and adjacent the wall thereof, radiant wall elements disposed obliquely across the flame from said burner and towards said wall, for radiating towards said wall heat which it absorbs from said flame, said elements being progressively overlapped side by side in a shingle-like manner, each element having upon the face engaged by said flame, a plurality of projections of greater altitude than base, for increasing the heat absorption and radiation of said elements.

3. A gas burner for use in heating devices having a fire box, comprising a burner disposed in said fire box and extending along and adjacent the wall thereof, radiant wall elements disposed obliquely across the flame from said burner and towards said wall, for radiating towards said wall heat which it absorbs from said flame, said elements being progressively overlapped, the overlapping 130

- surfaces being warped surfaces insuring a continuous line of contact between adjacent elements independently of the degree of overlap and of variations in spread at the 5 top when used with fire pots of different diameter.
4. A gas burner for use in heating devices having a fire box, comprising a burner disposed in said fire box and extending along and adjacent the lateral wall thereof, and a 10 plurality of radiant elements disposed in an inclined position across the plane of said burner and at their upper ends resting against said wall, said elements overlapping progressively side by side in a shingle-like manner along said wall, each element having oblique faces along opposite side edges for contacting with and overlapping the 15 next adjacent element.
5. A gas burner for use in heating devices having a fire box, comprising a burner disposed in said fire box and extending along and adjacent the lateral wall thereof, and a 20 plurality of radiant elements disposed in an inclined position across the plane of said burner and at their upper ends resting against said wall, said elements overlapping progressively side by side in a shingle-like manner along said wall, each element having oblique faces along opposite side edges for contacting with and overlapping the 25 next adjacent element, said oblique faces being warped surfaces permitting contact of overlapping faces along approximately their 30 entire lengths for considerable variations in the spread of the upper ends of said element, and also permit variations in the degree of overlap of said elements.
6. A gas burner for use in heating devices 35 having a fire box, comprising a burner disposed in said fire box and extending along, and adjacent the lateral wall thereof, a plurality of radiant elements in the form of tapered plates wider at one end than the 40 other, arranged side by side, and progressively overlapping in a shingle-like manner, said elements extending obliquely across the flame from said burner, and at their upper ends resting against said wall, the under 45 faces of said elements at their upper ends 50
- being concave to provide spaces between the same and the lateral wall against which it rests, through which the gases of combustion from said burner may pass.
7. A radiant element for use in heating devices having a fire pot, comprising a plate-like strip of fire resisting, radiant material tapered in width from end to end and having warped beveled surfaces along opposite side edges. 55
8. A radiant element for use in heating devices having a fire pot, comprising a plate-like strip of fire resisting, radiant material tapered in width from end to end and having warped beveled surfaces along opposite side edges, said warped surfaces being provided upon opposite faces of said strip adjacent the side edges, said warped surfaces being provided upon opposite faces of said strip adjacent the side edges. 60
9. A radiant element for use in heating devices having a fire pot, comprising a plate-like strip of fire resisting, radiant material tapered in width from end to end and having warped beveled surfaces along opposite side edges, one of said faces adjacent the wider end being concave for some distance from that end. 65
10. A radiant element for use in heating devices having a fire pot, comprising a plate-like strip of fire resisting, radiant material tapered in width from end to end and having warped beveled surfaces along opposite side edges, one of the faces of said strip having a plurality of pronounced projections 70 for increasing its heat radiating effect and its absorption of heat from flames striking the same. 75
11. In combination with a fire box and a gas burner in the fire box, a plurality of radiant elements with their lower ends resting on a part of the burner, said radiant elements arranged in progressively overlapping manner, each such element resting near the top with a portion adjacent one 80 edge pressing against the fire box, and a portion adjacent the other edge pressing against the next adjoining element. 85

MILLARD J. ROBERTS.

DISCLAIMER

1,725,304.—*Millard J. Roberts, Buffalo, N. Y. GAS BURNER AND THE LIKE.* Patent dated August 20, 1929. Disclaimer filed October 15, 1930, by the assignee, *Roberts-Gorden Appliance Corporation*.

Hereby enters the following disclaimer in relation to certain of said claims as follows:

Your petitioner disclaims from the scope of claims 1, 6, and 11 any overlapping of adjacent elements, in which an element adjacent its upper end contacts with or is approximately in contact with the fire box at or adjacent to both side edges of said element, as shown in the patent to Ebinger No. 753,250, of March 1, 1904.

[*Official Gazette November 11, 1930.*]

- surfaces being warped surfaces insuring a continuous line of contact between adjacent elements independently of the degree of overlap and of variations in spread at the 5 top when used with fire pots of different diameter.
4. A gas burner for use in heating devices having a fire box, comprising a burner disposed in said fire box and extending along and adjacent the lateral wall thereof, and a 10 plurality of radiant elements disposed in an inclined position across the plane of said burner and at their upper ends resting against said wall, said elements overlapping progressively side by side in a shingle-like manner along said wall, each element having oblique faces along opposite side edges for contacting with and overlapping the 15 next adjacent element.
5. A gas burner for use in heating devices having a fire box, comprising a burner disposed in said fire box and extending along and adjacent the lateral wall thereof, and a 20 plurality of radiant elements disposed in an inclined position across the plane of said burner and at their upper ends resting against said wall, said elements overlapping progressively side by side in a shingle-like manner along said wall, each element having oblique faces along opposite side edges for contacting with and overlapping the 25 next adjacent element, said oblique faces being warped surfaces permitting contact of overlapping faces along approximately their 30 entire lengths for considerable variations in the spread of the upper ends of said element, and also permit variations in the degree of overlap of said elements.
6. A gas burner for use in heating devices 35 having a fire box, comprising a burner disposed in said fire box and extending along, and adjacent the lateral wall thereof, a plurality of radiant elements in the form of tapered plates wider at one end than the 40 other, arranged side by side, and progressively overlapping in a shingle-like manner, said elements extending obliquely across the flame from said burner, and at their upper ends resting against said wall, the under 45 faces of said elements at their upper ends 50
- being concave to provide spaces between the same and the lateral wall against which it rests, through which the gases of combustion from said burner may pass.
7. A radiant element for use in heating devices having a fire pot, comprising a plate-like strip of fire resisting, radiant material tapered in width from end to end and having warped beveled surfaces along opposite side edges. 55
8. A radiant element for use in heating devices having a fire pot, comprising a plate-like strip of fire resisting, radiant material tapered in width from end to end and having warped beveled surfaces along opposite side edges, said warped surfaces being provided upon opposite faces of said strip adjacent the side edges, said warped surfaces being provided upon opposite faces of said strip adjacent the side edges. 60
9. A radiant element for use in heating devices having a fire pot, comprising a plate-like strip of fire resisting, radiant material tapered in width from end to end and having warped beveled surfaces along opposite side edges, one of said faces adjacent the wider end being concave for some distance from that end. 65
10. A radiant element for use in heating devices having a fire pot, comprising a plate-like strip of fire resisting, radiant material tapered in width from end to end and having warped beveled surfaces along opposite side edges, one of the faces of said strip having a plurality of pronounced projections 70 for increasing its heat radiating effect and its absorption of heat from flames striking the same. 75
11. In combination with a fire box and a gas burner in the fire box, a plurality of radiant elements with their lower ends resting on a part of the burner, said radiant elements arranged in progressively overlapping manner, each such element resting near the top with a portion adjacent one 80 edge pressing against the fire box, and a portion adjacent the other edge pressing against the next adjoining element. 85
